Primary Examiner — Stacia Cadmus

(57) **CLAIM**

The ornamental design for an automotive wheel, as shown and described.

DESCRIPTION

FIG. 1 is a perspective view of an automotive wheel, showing my new design; and,

FIG. 2 is a front view thereof.

The broken line showing of the rear portion of the rim is included for the purpose of illustrating environment and forms no part of the claimed design.

1 Claim, 2 Drawing Sheets

FIG. 1

FIG. 2
